UNITED STATES PATENT OFFICE.

FRANK O. HOAGLAND, OF HARTFORD, CONNECTICUT, ASSIGNOR TO PRATT & WHITNEY COMPANY, OF HARTFORD, CONNECTICUT, A CORPORATION OF NEW JERSEY.

METAL-WORKING MACHINE.

1,323,277.

Specification of Letters Patent.

Patented Dec. 2, 1919.

Application filed May 10, 1917. Serial No. 167,640.

To all whom it may concern:

Be it known that I, FRANK O. HOAGLAND, a citizen of the United States, residing at Hartford, in the county of Hartford and

5 State of Connecticut, have invented certain new and useful Improvements in Metal-Working Machines, of which the following is a specification.

This invention relates to a machine which 10 is similar in many respects to that set forth in my contemporaneously pending application filed April 5, 1917, Serial No. 159,883. The present machine like that in said other application can be utilized in widely-dif- 15 ferent arts, although it is of especial advantage in the production of bullets such for instance as are used in small arms. The present machine, like that in the aforesaid application, comprises mechanism for sup- 20 porting a blank and for supplying to the blank one or a succession of blows upon its surface. In the earlier application before referred to, I have shown a machine hav- 25 ing two rotatable rollers for applying a plurality of blows in rapid succession to the surface of the blank, these blows being delivered by means of ribs formed on the surface of two rapidly rotating rollers ar- 30 ranged side by side. In the present case I make use of an outer annular roller and an inner roller which is surrounded by the outer roller and which is arranged eccen- 35 trically with respect thereto. The bullet blank is engaged and acted upon by the surfaces of the two rollers at the throat where the surfaces are close together.

In the drawings accompanying and forming part of the present specification I have shown in detail a machine embodying the 40 invention and which is well adapted for my purposes. However, I do not restrict myself to this particular disclosure, and I may depart therefrom in several respects within the scope of the invention defined by the 45 claims following the description.

Of the drawings:

Figure 1 is a plan view, partly in section,

showing the rollers and the driving means therefor.

Fig. 2 is a detail view in sectional elevation of the outer roller. 50

Fig. 3 is a view on an enlarged scale of a portion of the operative part of the outer roller.

Fig. 4 is a like view of a portion of the 55 periphery of the inner roller.

Fig. 5 is an end view, partly in section, showing the rollers and the devices for feeding and supporting the blanks.

Fig. 6 is a front view, partly in section, 60 showing the mechanism illustrated in Fig. 5.

Fig. 7 is a detail view of the supporting device.

Fig. 8 is a detail view of one of the cams and the member coöperating therewith. 65

Fig. 9 is a view similar to Fig. 4 but showing an alternate form of inner roller.

Like characters refer to like parts throughout the several views which it will be obvious, are on different scales. 70

The different parts of the machine may be supported by any suitable framework. That shown for the purpose is denoted in a general way by 2. Use is made of two rollers as 3 and 4 having circular cross sections, the roller 3 inclosing or surrounding the roller 4 and both being rotative about preferably horizontal axes which are in parallelism. The outer roller 3 as shown extends centrally from and is integral or at 75 least rigid with a journal-piece 5 rotative in a suitable bearing-opening in the framework 2. The journal-piece has at its rear a web 6 provided with a peripheral flange 7. As shown the flange 7 has gear teeth 8 on its inner surface, so that the flange 7 and web 6 constitute an internal gear. These teeth 8 mesh with the teeth of a pinion 9 on a shaft 10 adapted to be driven in any desirable way. The roller 3 and journal-piece 90 5 are hollow and through them extends a shaft 11, having at its front end the roller 4 in coöperative relationship with the roller 3 as will hereinafter more particularly ap-

75

70

75

85

90

pear. A pinion 14 is connected with the shaft 11 and is adapted to mesh with the teeth 8. The teeth are actually in mesh, as will hereinafter more particularly appear, 5 when the rollers 3 and 4 are relatively positioned for rolling a blank into finished shape. The roller 3 is rabbeted out as at 15 to receive the roller 4 as shown best in Fig. 1 and as also indicated in Figs. 2, 5 and 6. 10 This roller 4 has a movement bodily as will hereinafter more particularly appear to permit of the positioning of a blank to be rolled.

The shaft 11, which it will be remembered 15 carries the roller 4, is carried by eccentrics 16 which are operated by toggles 17. These toggles are controlled in suitable manner to move the eccentrics so as to effect the movement of the roller 4 bodily toward and 20 from the companion roller 3. The rollers are shown in working relation in Fig. 5, the toggle 17 being straightened. When the roller 4 is in working relation it is slightly separated from the operative or inner surface 25 face of the roller 3 slightly, as shown in Figs. 1 and 5. The minimum distance at the throat of the rollers between the operative faces represents virtually the transverse extent of the finished article. The toggles 17 30 can be operated in any suitable manner, it being clear that they are flexed to effect the movement of the roller 4 bodily toward the left in Fig. 5 and thus permit the positioning of a blank. When the blank is in position 35 to be rolled, the roller 4 is moved toward the roller 3 and, as both are rotating at this time, the blank will be rolled to effect the desired purposes. In the present case as in my prior application when the article 40 is finished, the longitudinal center line will pass through the center of gravity thereof which is an important if not vital matter. In addition to this I remove projections that may be on the blank, the bullet when discharged from the machine being smooth. 45

The outer roller 3 has on its inner surface ribs 18 which are annular or circular, their sides converging outwardly. Transversely the inner or operative surface of the hollow 50 roller 3 is arched or concaved to conform to the longitudinal curvature of the blank. The peripheral portion of the roller 4 is similarly arched or concaved to conform to the longitudinal curvature of the blank or 55 bullet. The roller 4 preferably has on its outer side practically rectangular projections 19, as shown in Fig. 4. These projections are arranged in rows, the projections of the respective rows being transversely 60 staggered as shown. The inner roller 4 is also provided with rows of marginal projections 20 and 21 similar to the projections 19. It will be clear that the inner roller 4 is pe-

ripherally corrugated or toothed so as to apply a succession of blows to the blank between it and the companion roller 3. 65

These two rollers 3 and 4 constantly rotate, the roller 4 as will be clear being separated from the roller 3 to permit the introduction of a blank therebetween, and as I 70 have already explained, the toggles 17 in connection with the eccentrics 16 effect this separation. The blanks travel through a chute 22 and are moved therefrom by a rod 23 located at the upper end of a rocker lever 75 24 fulcrumed between its ends to a bracket or bearing 25 on the framework 2. The lower end of this rocking lever 24 is engaged and operated by a cam 26 on a horizontal power shaft 27. The rod 23 acts to push blanks from the 80 chute 22 into a delivery member 28. From the delivery member the blanks are pushed by a rod 29 extending from a block 30 supported by a guide way 31 on the bracket 25. To this block or slide 30 is connected a 85 lever 32 fulcrumed between its ends on the bracket 25. The lever 32 carries a stud 33 which enters a peripheral groove in a cam 34 on the power shaft 27. The lever 32 is operated by the cam and it in turn pushes the 90 block 30 to cause the rod 29 to push a blank from the holder 28 into a supporting device such as that denoted in a general way by 35. The supporting device 35 which is shown in detail in Fig. 7 comprises an upper jaw 36 95 which may as shown be rigid with the part 28 and a lower movable jaw 39. The operative portions of the jaws 36 and 39 are longitudinally curved to receive a bullet blank 40, the jaws loosely holding the blank while it is being rolled. At the conclusion of the rolling operation the lower jaw 39 is positively moved away from the upper jaw 36 in suitable manner. To accomplish this result, jaw 39 is connected with a horizontally movable plunger 41, which is pivotally connected with the upper end of a lever 42. The lever 42 is pivotally mounted on the bracket 25 and the lower end of the lever engages a cam 46 fixed to the power shaft 27. On the 100 movement of the jaw 39 outward in the direction indicated by dotted lines in Fig. 7, it strikes the holder 28 and is thus moved downward, as indicated. This combined outward and downward movement serves to 105 effect the separation of the rolled blank 40 from between the jaws, the blank then falling into the receiving end of a delivery chute 47.

In Fig. 9 I show an inner roller 50 which 110 as will be understood acts like or is the equivalent of the roller 4. This roller 50 may and preferably does operate exactly like the roller 4. The two differ, however, in their surface formation, the roller 50 having transverse parallel ribs 51 throughout 115

its entire extent. These ribs or corrugations 51 are concaved longitudinally to conform to the longitudinal convexity of the roller 50.

Taking up the operation of the machine, 5 let it be supposed that the rollers 3 and 4 are rotating and that the roller 4 has been moved laterally toward the left to permit the positioning of a blank between the rollers. It will be understood that the movement 10 of the roller 4 is effected by flexing the toggles 17. With the roller 4 thus laterally moved, the rod 29 is advanced through the action of the cam 34 in the manner already described to push a blank from the 15 delivery member or holder 28 in between the jaws 36 and 39. When this is accomplished the toggles 17 are straightened to move the rotating roller 4 into contact with the blank so as to roll the blank and peripherally 20 smooth it. The jaws 36 and 39 in the construction shown prevent any movement of the blank 40 except the turning thereof about its longitudinal axis. When the blank is smoothed the plunger 41 is drawn back 25 by the action of the cam 46 in the manner already described, carrying the finished blank therewith, the jaw 39 striking the part 28 on its backward movement and freeing the finished blank which is then discharged 30 into the upper end of the delivery chute 47.

What I claim is:

1. A machine of the class described comprising internal and external rollers having circular cross sections, and means for 35 presenting a blank between the rollers, the rollers having means on their adjacent surfaces coöperating to smooth the blank.

2. A machine of the class described comprising internal and external rollers having 40 circular cross sections, and means for presenting a blank between the rollers, the rollers having means on their adjacent surfaces coöperating to smooth the blank and one of the surfaces being roughened.

45 3. A machine of the class described comprising internal and external rollers having circular cross sections, and means for presenting a blank between the rollers, one of the rollers having a series of spaced ribs, 50 the other roller having peripheral projections, the projections being transverse to the ribs.

4. A machine of the class described comprising internal and external rollers having 55 circular cross sections, and means for presenting a blank between the rollers, the inner surface of the external roller having ribs which are parallel to each other and which are concentric with the axis of rotation of said roller, the other roller having on its surface transverse projections.

5. A machine of the class described comprising internal and external rollers hav-

ing circular cross sections, and means for presenting a blank between the rollers, the 65 internal roller having external projections in staggered relation to each other.

6. A machine of the class described comprising internal and external rollers having circular cross sections, and means for 70 presenting a blank between the rollers, the rollers having means on their adjacent surfaces coöperating to smooth the blank, the blank presenting means also having means to prevent bodily movement of the blank 75 during the rolling operation.

7. A machine of the class described comprising internal and external rollers having circular cross sections, means for presenting a blank between the rollers and for 80 preventing its bodily movement yet free rotation while between the rollers, the latter having means on their adjacent surfaces coöperating to smooth the blank.

8. A machine of the class described comprising internal and external rollers having circular cross sections, the adjacent surfaces of which are dished, the rollers when in active relation being separated from each other, and means for presenting a blank between the rollers, the rollers having means on their concaved surfaces coöperating to smooth the blank. 90

9. In a bullet making machine, the combination of inner and outer relatively eccentric rollers rotatable about approximately parallel axes and having their surfaces provided with generally longitudinal ribs, and means adapted to engage a bullet blank at opposite sides thereof and to support it at the throat of the rollers in position to be engaged by both of them, the said supporting means serving to hold the blank against bodily movement under the influence of the rollers. 95

10. In a bullet making machine, the combination of inner and outer relatively eccentric rollers rotatable about approximately parallel axes and having their surfaces provided with generally longitudinal ribs, and means adapted to engage a bullet blank at opposite sides thereof and to support it at the throat of the rollers in position to be engaged by both of them, the said supporting means serving to hold the blank against bodily movement during the rolling operation. 105

11. In a bullet making machine, the combination of inner and outer relatively eccentric ribbed rollers rotatable about approximately parallel axes, means adapted to engage a bullet blank at opposite sides thereof and to support it at the throat of the rollers in position to be engaged by both of them, and means for bodily moving one of the rollers relatively to the other to increase the 110

115

120

125

width of the throat and thus permit the insertion of a blank.

12. In a bullet making machine, the combination of inner and outer relatively eccentric ribbed rollers rotatable about approximately parallel axes, means adapted to engage a bullet blank at opposite sides thereof and to support it at the throat of the rollers in position to be engaged by both of them, 5 means for bodily moving one of the rollers relatively to the other to increase the width

of the throat and thus permit the insertion of a blank and for then returning the roller to normal position, and means for supplying a blank to the supporting means when 15 the roller has been moved as aforesaid.

In testimony whereof I affix my signature in the presence of two witnesses:

FRANK O. HOAGLAND.
